CARRYING HANDLE FOR CONTAINERS

Daniel Belcher, Minneapolis, Minn., assignor to
 Bemis Bro. Bag Co., Minneapolis, Minn., a corporation of Missouri

Application April 29, 1935, Serial No. 18,860

11 Claims. (Cl. 229—54)

This invention relates to new and useful improvements in carrying handles for containers, and is an improvement over the form shown in my pending application, Serial No. 11,586, filed 5 March 18, 1935.

An object of the present invention is to provide a carrying device for containers or paper bags whose top wall portions have been folded into closing and sealing relation, which comprises a 10 pair of elements adapted to be inserted between the folded top wall portions of the container and having a flexible member slidably engaged therewith and forming a carrying handle for the bag, the connections between said member and elements being such that when a pull is exerted upon the member, the elements are 15 urged into operative positions between the folds of the bag top.

A further object is to provide a carrying device 20 for sealed paper bags comprising a pair of plate elements having spaced openings therein, and an endless taped member being threaded through said openings and having a portion forming a carrying handle for the bag, said plate elements having portions adapted to be inserted between the 25 folds of the closed bag top.

A further object is to provide a simple and inexpensive carrying device for paper bags whose top wall portions have been folded into closing 30 and sealing relation, which device may readily be attached to the closed top of a bag, and which is so constructed that when in use, it cannot accidentally become detached from the bag top.

Other objects of the invention will appear from 35 the following description and accompanying drawing and will be pointed out in the annexed claims.

In the accompanying drawing there has been 40 disclosed a structure designed to carry out the various objects of the invention, but it is to be understood that the invention is not confined to the exact features shown as various changes may be made within the scope of the claims which follow.

45 In the drawing:

Figure 1 is a perspective view showing a closed bag top with the novel carrying device attached thereto;

50 Figure 2 is a perspective view to show how the side flaps of the bag top are preferably gummed before being folded into closing and sealing relation;

55 Figure 3 is a perspective view showing the device detached from the bag top;

Figure 4 is an enlarged detail sectional view showing how the tape is threaded through the openings in the plate elements; and

Figure 5 is a view showing a device of slightly different construction.

The novel carrying device herein disclosed, and as illustrated in Figure 3, is shown comprising a pair of plate elements 2 having spaced openings or slots 3 and 4 therein, through which a suitable flexible member or tape 5 is threaded. The 10 ends of the tape member 5 are suitably secured together by such means as stitching, as shown at 6 in Figure 3.

By threading the tape member 5 through the slots 3 and 4, as above described, the plate elements 2 are movable or slidable upon the tape, whereby they may readily be spread apart, as shown in full lines in Figure 4, to facilitate inserting them between the folded wall portions of the bag top, as best illustrated in Figure 1. It is 15 to be understood that the side flaps 7 and 8 have only their intermediate portions secured by gumming, as indicated at 9 in Figure 2, whereby the plate elements 2 may readily be inserted between 20 ungummed portions of the flaps 7 and 8, as shown 25 in Figure 1.

When the plate elements are attached to the bag top, as shown in Figure 1, and a pull is exerted on the handle portion of the tape 5, an inward force is exerted on the plate elements 2, 30 as a result of the tape being threaded through the slots 3 and 4 thereof, as will readily be understood by reference to Figures 1 and 3. This results because the tape is loosely threaded through the slots in the plate elements, so that 35 when a pull is exerted on the upwardly looped portion of the tape, the plate elements are urged inwardly towards each other. It will thus be seen that when the bag is carried by the novel carrying device herein disclosed, the plate elements of said device cannot accidentally become 40 detached from the bag top.

The device is very simple and inexpensive in construction, and may be manufactured at small cost. Its construction is such that it may readily 45 be stored or packed in a comparatively small space, when not in use, and may be quickly attached to the bag top, when desired. Because of the ends of the tape 5 being secured together, as illustrated at 6 in Figures 1 and 3, the plate elements 2 cannot become detached from one another, whereby they become a component part 50 of the carrying device, so that the latter is always intact and ready for use, when the occasion arises. 55

Figure 5 illustrates a form in which a pair of wire elements 11 are used to secure the device to the bag top in place of the plate elements shown in the previous figures. Each wire element has 5 an eye or loop 12 formed in its intermediate portion, through which a flexible cord or tape 13 is threaded. The ends of this cord may be suitably united, as shown at 14.

The device shown in Figure 5 is used in identically the same manner as that shown in the previous figures. The terminals of the wire elements 11 are inserted between the folded wall portions of the bag top, as shown, and when the cord 13 is grasped by the hand and a pull exerted thereon, the wire elements are urged towards each other by the action of the cord, thereby positively preventing the device from becoming detached from the bag top, when in use.

I claim as my invention:

20 1. A carrying device for a paper bag whose top wall portions have been folded into closing relation to close and seal the bag top and whereby certain of said folded wall portions may be partially separated to provide openings therebetween, 25 said carrying device comprising, a pair of elements having portions adapted to be inserted in the openings between the folded bag top walls, and a carrying member having a sliding connection with said elements and adapted, when a pull is exerted thereon, to draw said elements into said 30 openings, whereby they cannot readily become detached from the bag top when the container is carried by said device.

2. A carrying device for a paper bag whose top 35 wall portions have been folded into closing relation to close and seal the bag top and whereby certain of said folded wall portions may be partially separated to provide openings therebetween, said carrying device comprising, a pair of plate elements adapted to be inserted in openings provided between the folded bag top walls, and a carrying member having operative connections with said plate elements and adapted, when a pull is exerted thereon, to force said elements towards each other, whereby they cannot readily become detached from the bag top, when the bag is carried by said device.

3. A carrying device for a paper bag whose top 40 wall portions have been folded into closing relation to close and seal the bag top and whereby certain of said folded wall portions may be partially separated to provide openings therebetween, said carrying device comprising, a pair of plate elements adapted to be inserted in openings 45 provided between the folded bag top walls, and a flexible carrying member slidably connected to said plate elements and adapted, when a pull is exerted thereon, to urge said elements into operative positions between the folded walls of the bag top, thereby to prevent them from accidentally becoming detached from the bag top, when the bag is carried by said device.

4. A carrying device for paper bags whose top 50 wall portions have been folded into closing and sealing relation against the bag body and whereby said folded walls may be partially separated to provide oppositely disposed openings, said device comprising a pair of plate elements adapted to be inserted in said openings, a flexible member 55 movably connected to said plate elements and movable with respect thereto, said member having a portion forming a carrying handle whereby the bag may be carried, and the connections between said flexible member and said plate elements being such that when a pull is exerted 60

upon said handle portion, the plate elements are urged into operative positions between the folds of the bag top walls.

5. A carrying device for paper bags whose top 5 wall portions have been folded into closing and sealing relation and whereby said folded walls may be partially separated to provide oppositely disposed openings, said device comprising a pair of plate elements adapted to be inserted in said 10 openings, said elements having spaced slots therein, an endless tape threaded through said slots and having a portion adapted to form a carrying handle for the bag and having another portion engaging the top of the bag, said tape being adapted to urge said plate elements towards each 15 other when a pull is exerted thereon, whereby the elements cannot accidentally become detached from the closed bag top when in use.

6. A carrying device for paper bags whose top 20 wall portions have been folded into closing and sealing relation and whereby said folded walls may be partially separated to provide oppositely disposed openings, said device comprising a pair of plate elements and having a flexible tape member slidably connected thereto and forming 25 a carrying handle, said plate elements being adapted to be inserted into the openings between the folded bag top walls from opposite sides of the bag top whereby, when a pull is exerted on said member, the slidable connection between the 30 member and plate elements will urge said plate elements into operative positions between the folded walls of the bag top.

7. A carrying device for paper bags whose top 35 wall portions have been folded into closing and sealing relation and whereby certain of said folded wall portions may be separated to provide openings therebetween, said device comprising a pair of plate elements whose ends may be inserted into said openings to attach the device to 40 the bag top, said plate elements having apertures therein, and a tape threaded through said apertures and forming a handle.

8. A carrying device for paper bags whose top 45 wall portions have been folded into closing and sealing relation and whereby certain of said folded wall portions may be separated to provide openings therebetween, said device comprising a pair of plate elements whose ends may be inserted into said openings to attach the device to the 50 bag top, said plate elements having spaced slots therein, and a tape threaded through said slots and forming a handle.

9. In a carrying device for paper bags whose top wall portions have been folded into closing 55 and sealing relation and whereby said folded walls may be partially separated to provide oppositely disposed openings, said device comprising a pair of wire elements having eyes formed in their intermediate portions, the terminals of 60 said elements being adapted to be inserted in the openings between the folded wall portions, thereby to attach the device to the bag top, a flexible member having a running connection with the eyes of said elements and forming a handle 65 whereby the bag may be carried, the connections between said member and said elements being such that when a pull is exerted on the member, the elements are urged towards each other whereby they cannot readily become detached 70 from the bag top, when the device is in use.

10. A carrying device for paper bags whose top wall portions have been folded into closing relation and whereby certain of said folded wall portions may be separated to provide openings 75

therebetween, said device comprising elongated wire elements having portions adapted to be inserted into said openings to attach the device to the bag top, each of said elements having an eye formed in its intermediate portion, and a cord threaded through said eyes and having its ends suitably united thereby to inseparably connect together said elements, and said cord forming a carrying handle, when the device is attached to a bag top.

5 10 11. A carrying device for paper bags whose top wall portions have been folded into closing and

sealing relation and whereby certain of said folded wall portions may be separated to provide openings therebetween, said device comprising a pair of elements having oppositely disposed terminals adapted to be inserted into said openings to attach the device to the bag top, each element having an aperture therein, and an endless member threaded through said apertures and inseparably connecting them together and also forming a carrying handle.

5 10

DANIEL BELCHER.
